US00D986917S

(12) **United States Design Patent** (10) **Patent No.:** **US D986,917 S**
Baker et al. (45) **Date of Patent:** **** May 23, 2023**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Rhodes B. Baker**, Bethlehem, PA (US);
John H. Bull, Coplay, PA (US); **Erica L. Clymer**, Northampton, PA (US);
Sanjeev Kumar, Harleysville, PA (US);
Jennifer Wong, Breinigsville, PA (US)

(73) Assignee: **Lutron Technology Company LLC**,
Coopersburg, PA (US)

(**) Term: **15 Years**

(21) Appl. No.: **29/735,507**

(22) Filed: **May 21, 2020**

Related U.S. Application Data

(63) Continuation of application No. 29/657,865, filed on Jul. 26, 2018, now Pat. No. Des. 885,417, which is a continuation of application No. 29/610,598, filed on Jul. 13, 2017, now Pat. No. Des. 826,975, which is a continuation of application No. 29/535,336, filed on Aug. 5, 2015, now Pat. No. Des. 794,669.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The broken lines illustrate a display screen or portion thereof and form no part of the claimed design.
